UNITED STATES PATENT OFFICE.

JOSHUA R. RAY AND THOMAS RAY, OF MANISTEE, MICHIGAN.

CHIPPING-MACHINE.

1,039,441.

Specification of Letters Patent. Patented Sept. 24, 1912.

Application filed May 3, 1909. Serial No. 493,476.

To all whom it may concern:

Be it known that we, JOSHUA R. RAY and THOMAS RAY, both citizens of the United States, residing at Manistee, in the county 5 of Manistee and State of Michigan, have jointly invented a certain new and useful Improvement in Chipping-Machines, of which the following is a description.

Our invention relates to mechanism for 10 cutting a log or block of wood into shavings, chips, or pieces, of substantially uniform size.

The object of our invention is to provide 15 a simple, strong, and efficient device of the kind described, arranged to produce chips or pieces of substantially uniform or any desired number of different dimensions in 20 length and width either of which dimensions may be changed to suit the particular purpose for which the chips are to be employed.

To this end our invention consists in the novel construction, arrangement, and combination of parts herein shown and described, 25 and more particularly pointed out in the claims.

In the accompanying drawings, wherein 30 like or similar reference characters indicate like or corresponding parts; Figure 1 is a side elevation of our device with parts removed and broken away to more clearly show the construction. Fig. 2 is a front elevation of the same. Fig. 3 is an enlarged detail of the movable wall of the chute for 35 directing the material to the cutter together with a portion of the piston-rod for controlling its position. Fig. 4 is a top plan view of our device. Fig. 5 is a sectional detail of the operating valve for controlling the cross- 40 section of the chute. Fig. 6 is an elevation of the preferred form of cutter blade of our device. Fig. 7 is a detail of the mechanism for preventing longitudinal movement of the cutter head shaft. Fig. 8 is a front elevation of the cutter head of our device. Fig. 45 9 is a section taken substantially on line 9—9 of Fig. 8; and Fig. 10 is an enlarged fragmentary detail of the cutter head.

In the preferred form shown in the drawings, 50 our device consists of a suitable frame or base-plate 1, upon which is mounted a pair of bearings 2 and 3 or equivalent means. A shaft 4 is supported jointly in the bearings 2 and 3 and provided intermediate its 55 ends with a cutter head 5 and a drive pulley 6 or any suitable means for rotating said

shaft and cutter head. The cutter head 5 may be of any desired form, size, or construction. As shown this part consists of a suitably formed disk rigidly secured to the 60 shaft and having one substantially flat face 7 provided with a plurality of angular or V-shaped slots 8—8 extending through the head. A portion of the cutter head adjacent each slot 8 is formed to operate as a seat 15 for receiving a cutter blade 9 and securely holding the same in position in the head 5. Each of the blades 9 is preferably positioned in a slot 8 with its cutting edge projecting at the face 7 of the cutter head 70 a suitable distance to engage the material to be cut and produce a chip of the desired length. The two portions of each slot are arranged to diverge toward the direction of rotation of said head from a circle concentric to the cutter head, that is, when the cutter head is in operation the several blades secured to the head will have their edge adjacent the common concentric line above referred to, at the rear of the opposite edge 80 of the blade, that is, the general line of the cutting edge of each blade will incline rearwardly and toward said circle.

Any suitable form or construction of cutting blade may be provided. In the form 85 shown a substantially independent cutting blade 9 is provided for each portion of each slot 8, or if preferred a plurality of substantially independent blades may be provided depending upon the method employed 90 for securing the blades in position, and the form of the chips desired.

As shown in Fig. 6, the cutting blade is provided with a plurality of substantially V-shaped grooves formed in its face extending 95 to the cutting edge of the blade, so arranged that the cutting edge of each blade consists of a connected series of V-shaped notches. One edge of each notch is preferably sharpened and adapted to serve as a 100 cutting portion so that when the blade is positioned in its slot and properly secured in position as shown in Fig. 10, a series of substantially independent cutting portions 11 are presented at the face of the head 5 each 105 extending in a radial direction to the cutter head 5 and adapted to operate substantially independently thereby forming a series of chips or shavings, each chip or shaving corresponding in width to the width of the 110 cutting portion 11 by which it is formed and extending across the entire surface pre-

sented to the cutters of the material being operated upon.

In the preferred construction shown the grooves 10 are substantially of uniform size and form so that the several cutting portions 11 of each blade will be of the same size and will cut a substantially equal amount of material thereby producing chips or shavings of substantially uniform dimensions. It is 10 obvious however that if desired the size and form of groove 10 may be altered to suit any peculiar condition which may be presented so that the width of the cutting portions 11 will not be uniform and will therefore produce chips or shaving varying in size. The blades 9—9 may be secured in position upon the head 5 in any suitable manner. In the form shown each blade is provided with suitable slots 12 or equivalent means and a 15 cap-screw 14 or other suitable holding device is provided arranged to extend through each slot into suitable threaded holes in the blade seat 15 of the cutter head for this purpose.

To secure the best results it is often desirable to adjust the size of the opening 8 through which the blades 9—9 project and for this purpose a throat-plate 16 or equivalent means is provided upon the face 7 of the cutter head, suitably formed to control the 20 width of the opening 8 as desired. Any suitable means may be provided for rigidly securing the throat-plate 16 in position. In the form shown a recess or depression is formed in the face 7 of the cutter head 5 of 25 suitable form and depth to receive the throat-plate and bring its outer face just flush with the face 7. A plurality of slotted openings 17 are formed through the throat-plate and a suitable cap-screw 18 is provided for each opening extending into a suitable hole in the cutter head 5 to hold the plates in position in the recess. The openings 17 and screws 18 are so formed that when the screws are in place holding the 30 plate in position no part of the screws will project beyond the face of the plate.

Means are provided for directing the material to be operated upon to the cutter head. In the form shown a frame or housing 19 35 is mounted upon the base 1 and provided with a chute 20 suitably inclined to the face of the cutter head so that the cutting blade will operate upon the material in the chute with a drawing, or shearing action with the 40 grain of the wood. In the preferred construction shown the upper side of the chute 20 is arranged to be moved transversely of the chute to control the cross-section of the chute and to prevent as far as possible the 45 movement of the material during the cutting operation.

Any suitable means may be provided for adjusting the position of the movable side 21 and also for firmly locking the same in its 50 adjusted position. In the form shown a

suitable cylinder 22 is provided upon the housing 19 having a piston 23 fitted to its interior. A piston rod 24 is attached to the piston 23 and extends through both heads of the cylinder so as to guide the piston rod, 55 and piston 23. The movable side 21 of the chute is rigidly secured to the lower end of the piston rod 24 as shown in Fig. 3. The usual or any preferred means may be provided for controlling the movement of the piston 23 in the cylinder. In the form shown pipes 25 and 26 are attached to the upper and lower ends of the cylinder 22 respectively and each extend to a four-way cock or valve 27 to which is also attached a 60 suitable supply pipe 28 for conducting water or other fluid under pressure to said device and an exhaust pipe 29 for discharging the fluid from the cylinder.

The valve 27 may be of any suitable form. As shown (Fig. 5), this valve is provided with a central opening 30 of the usual or any preferred form and the ports leading from the pipes 25, 26, and 28 to this central opening are each preferably of substantially 65 the same cross-sectional area, while the port leading from the central opening to the exhaust pipe 29 is preferably very much smaller so that when the movable portion 31 of the valve is positioned as shown in Fig. 75 5, the passage of fluid from the supply pipe 28 to the upper end of the cylinder through the pipe 25 will be comparatively free and unobstructed while the passage of fluid from the lower end of the cylinder through the 100 pipe 26 to the exhaust pipe 29 will be very much obstructed, thus securing a steady even movement of the parts and maintaining a considerable pressure upon the fluid thereby tending to firmly hold the piston in any position in the cylinder. Obviously when the part 31 of the valve is rotated to connect the pipe 26 with the supply pipe 28 and the pipe 25 with the exhaust pipe 29 the action 105 will be substantially the same as above described except that the piston and connected parts will be moved in the opposite direction. When it is desired to lock the piston in position in the cylinder it is only necessary to so position the rotatable part 31 that 110 its ports will not be in communication with any of the ports communicating with the several pipes connected to the valve thereby preventing the escape of fluid from either end of the cylinder and preventing any 115 movement of the piston in either direction.

In the preferred construction a hood or cover 32 is provided extending from the base plate 1 over the upper portion of the cutter head 5 and a bearing 33 is provided 120 for the extremity of the shaft 4 extending beyond the drive pulley 6.

In the form shown the adjacent edges of the blades 9 are adapted to lie in immediate contact with each other so that the blades 130

positioned in the two portions of the slot or opening 8 will operate substantially as a single blade. And it is obvious that if preferred a single blade of suitable form may 5 be employed in place of the two blades shown in each slot or any desired number of separate cutting blades may be provided in place of the single blades shown so long as the series of cutting portions 11 or their 10 equivalents are retained as shown in Fig. 10 of the drawings.

Any suitable means may be provided for holding the shaft 4 against longitudinal movement in the bearings and to receive the 15 thrust caused by the material in the chute pressing against the face of the cutter head 5. As shown a part 40 is provided at the center of the face 7 of the head 5 to press against one end of the bearing 2. The shaft 20 4 projects slightly beyond the end of the bearing 2 and is there provided with a longitudinally extended threaded opening 41 and a pin 42 or other suitable means adapted to engage and prevent rotation of the 25 cap 43 and distance pieces 44 positioned between the end of the shaft and the cap. In the form shown the cap 43 is provided with a central recess 45 to fit the end of the shaft 4 and with the parts outside the recess faced 30 or otherwise finished to bear against the end of the bearing 2 and coöperate with the part 40 of the head 5 to hold the shaft against longitudinal movement. A cap-screw 46 is provided extending through a central opening 35 in the cap 43 and engaging the opening 41 in the shaft to rigidly secure the cap in position.

In operation power is transmitted to the pulley 6 from any suitable source to rotate 40 the cutter head in the direction indicated in the drawings (Fig. 2), a strip or any desired number of strips or logs of wood are positioned in the chute 20 with their lower ends projecting through the chute into contact 45 with the face of the cutter head 5 so that each blade as it passes the material will remove a portion from the end of each of the strips or logs. The movable side of the chute 21 is moved down into close contact 50 with the material in the chute 20 but not sufficiently close to prevent the free movement of the strips by gravity in the chute, and as the material is cut away by the action of the blades upon the cutter head 55 other material is inserted in the chute and the movable side 21 is adjusted to suit the size and form of the same.

Having thus described our improvement, it is obvious that various immaterial modifications may be made in our device without departing from the spirit of our invention, hence we do not wish to be understood as

limiting ourselves to the exact form and construction shown.

What we claim as new, and desire to secure by Letters Patent is:—

1. In a device of the character described, a movable cutter head, means for supporting material to be acted on by said cutter head, and a cutting blade carried by said cutter head, the edge of said cutting blade being provided with a plurality of parallel separated cutting portions arranged parallel to the line of cut. 70

2. In a device of the character described, a rotatable disk, means for supporting material to be acted on, cutting means carried by and projecting from the face of said disk, said cutting means comprising a plurality of substantially parallel separated cutting 80 edges arranged in stepped relation and parallel to the line of cut.

3. In a device of the character described, a rotatable disk, and a cutting blade projecting from the face thereof, said blade being provided with a plurality of V-shaped notches in the edge thereof, the corresponding side of each notch being sharpened to provide a cutting portion, said cutting portions being parallel to each other and to the 90 line of cut. 85

4. In a device of the character described, a rotatable disk, a V-shaped cutting member carried thereby, the edges of which are provided with a plurality of separated cutting portions parallel to each other and to the line of cut. 95

5. In a device of the character described, a rotatable disk, a cutting blade projecting from the face of the disk with the edge 100 thereof extending at an angle to the radius of the disk, the edge of said cutting blade being provided with a plurality of separated cutting portions parallel to each other and to the line of cut. 105

6. In a device of the kind described, a rotatable disk, provided with slots therethrough for the reception of cutting blades, cutting blades for said slots each provided with a plurality of substantially V-shaped notches at its cutting edge, with one side of each notch formed to operate as a cutting portion, in combination with means for delivering the material to be operated upon to the face of the disk. 110

In testimony whereof, we have hereunto signed our names in the presence of two subscribing witnesses.
